UNITED STATES PATENT OFFICE.

ALBERT ENNIS HENDERSON, OF TORONTO, CANADA, ASSIGNOR TO TORONTO ROLLER BEARING COMPANY, LIMITED, OF TORONTO, CANADA.

ANTIFRICTION-BEARING.

SPECIFICATION forming part of Letters Patent No. 726,914, dated May 5, 1903.

Application filed November 13, 1902. Serial No. 131,170. (No model.)

To all whom it may concern:

Be it known that I, ALBERT ENNIS HENDERSON, a subject of the King of Great Britain, residing at Toronto, in the county of 5 York, Province of Ontario, Canada, have invented certain new and useful Improvements in Antifriction-Bearings, of which the following is a specification.

This invention relates to improvements in 10 antifrictional bearings; and the main object of my invention is the provision of an adjustably-journalized means carried by a tie-rod for forming spacing devices for the rollers, said tie-rods at the same time holding the retain- 15 ing-rings relatively to the bearing-rollers.

To attain these objects, the invention consists of a roller-bearing embodying novel features of construction, substantially as disclosed herein.

20 In the accompanying drawings, Figure 1 is a sectional view of a journal and boxing with my improved bearing in use thereon. Fig. 2 is a detail sectional view, enlarged, showing the construction of the tie-rod and its 25 connection with the retaining-rings. Fig. 3 is an elevation of a modified form of tie-rods, and Fig. 4 is a plan view of the inner side of one of the retaining-rings.

Referring to the drawings, the numeral 1 30 designates a shaft, 2 the boxing, and 3 the two retaining-rings, which are provided upon their inner faces with conical depressions 4 for the reception of the bearing-rollers. These retain- 35 ing-rings are also provided with openings 6 for the reception of the threaded pins 7, so that the tie-rods 8 may hold the retaining- 40 rings relatively to the bearing-rollers. These threaded pins are adapted to enter the threaded openings 9, formed in the ends of the tie- 45 rods, so as to project beyond the outer edge of the apertures or slots 10 of the tie-rods and engage the outer pintle 11 of the spacing-rollers 12, forcing the pintle 13 into the conical depressions 14, formed in the tie-rod upon the opposite side of the aperture and in alignment with the threaded openings of the tie-rod.

By means of the threaded pin the spacing- 50 rollers are adjustably journalized within the tie-rods, while at the same time the tie-rods are so connected with the retaining-rings as

to hold the retaining-rings relatively to the bearing-rollers. To form a lock for the threaded journals, I employ the nuts 15, which are adapted to contact the outer face of the 55 bearing-rings and hold the tie-rods securely in place. To prevent the tie-rods from turning after being secured in place, I provide the radial grooves 16 in the inner end of the retaining-rings to receive the outer ends of 60 the tie-rods.

In the modified form, as shown in Fig. 3, I cut away the tie-rods so as to provide the notch 17, the outer face being substantially the same as that shown in the preferred form. 65 This cut-away portion is formed upon the edge of the tie-rod nearest the axle.

From the foregoing description, taken in connection with the drawings, it is evident that I provide a tie-rod which adjustably secures the retaining-rings relatively to the bearing-rollers and at the same time contains adjustably-journalized spacing-rollers, so that the wear upon the pintles thereof may be readily taken up, and thus the proper adjustment at all times is provided for these rollers. 75

What I claim as new is—

1. In a roller-bearing, the combination of retaining-rings, bearing-rollers, apertured tie-rods for holding the retaining-rings relatively to the bearing-rollers, and antifriction-spacers adjustably mounted in the apertures of the tie-rods. 80

2. In a roller-bearing, the combination of the retaining-rings, the bearing-rollers, tie-rods for holding the retaining-rings relatively to the bearing-rollers, said tie-rods being provided with apertures, spacing-rollers mounted in said apertures, and means for connecting the tie-rods with the retaining-rings and 85 also for adjustably mounting the spacing-rollers in the apertures of the tie-rods. 90

3. In a roller-bearing, the combination of retaining-rings, bearing-rollers, tie-rods for holding the retaining-rings relatively to the bearing-rollers, and antifriction-spacers adjustably mounted in the tie rods. 95

4. In a roller-bearing, the combination of bearing-rollers, retaining-rings for the bearing-rollers provided with radial grooves upon their inner faces, tie-rods having their outer ends mounted in the radial grooves of the 100

retaining-rings, spacers mounted in the tie-rods, and means for securing the tie-rods in the grooves of the retaining-rings and adjustably supporting the spacers in the tie-rods.

5. In a roller-bearing, the combination of bearing-rollers retaining-rings provided with means to receive the bearing-rollers and means to receive tie-rods, tie-rods mounted in said latter means, spacers mounted in the tie-rods, and means for connecting the tie-rods to the retaining-rings and for adjustably mounting the spacers in the tie-rods.
- 10 6. In a roller-bearing, the combination of

bearing-rollers, retaining-rings for the bearing-rollers, apertured tie-rods spacers mounted in the apertures of said tie-rods, and means connecting the tie-rods with the retaining-rings and adjustably holding the spacers within the tie-rods.

15 In testimony whereof I affix my signature in presence of two witnesses.

ALBERT ENNIS HENDERSON.
